UNITED STATES PATENT OFFICE.

WILLIAM T. S. BROWN, OF EAST POINT, GEORGIA.

CONTAINER PARTITION.

Application filed December 18, 1923. Serial No. 681,438.

To all whom it may concern:

Be it known that I, WILLIAM T. S. BROWN, a citizen of the United States, residing at East Point, in the county of Fulton and State of Georgia, have invented certain new and useful Improvements in Container Partitions, of which the following is a specification, reference being had therein to the accompanying drawing.

10 This invention relates to boxes, crates, and other containers for holding commodities during shipment and storage, and it pertains particularly to a partition adapted for use therein.

15 My Letters Patent No. 1,468,340, September 18, 1923, shows a partition for boxes, crates, and the like that is satisfactory for use in knockdown and non-knockdown forms of such articles when the top, bottom, and

20 sides are made of rigid non-bulging material, but it is liable to become displaced in containers in which bulging occurs.

The present invention is directed to the provision of a partition having means associated therewith that are adjustable to permit such an amount of bulge as usually occurs and is desirable in the walls of boxes or crates in which citrus fruits, for example, are packed, and which at the same time will 25 remain reliably associated with the structure, afford a strengthening element between the ends of the structure, and prevent excessive bulge in the top, bottom, sides, or any of them.

30 When considered in connection with the description herein, the characteristics of the invention are apparent from the accompanying drawing, forming part hereof, wherein an embodiment of the invention is disclosed, 35 for purposes of illustration.

Although the disclosures herein exemplify what now is considered to be a preferable embodiment of the invention, it is to be understood that it is not the intention to be 40 limited necessarily thereto in interpretation of the claims, as modifications and adaptations within the limits of the claims can be made without departing from the nature of the invention.

45 Like reference-characters refer to corresponding parts in the views of the drawing, of which—

Fig. 1 is a view of a container;

50 Fig. 2 is an elevation of the partition, with a part of its wall being broken away,

the walls of the container being shown in section;

Fig. 3 is a section on the line 3—3, Fig. 2;

Fig. 4 is a view illustrative of a modification;

Fig. 5 is a fragmentary view illustrative of an alternative form;

Fig. 6 is a view of one of the fasteners;

Fig. 7 is a view of an alternative form 65 of fastener;

Fig. 8 is a view of a fastener associated with a solid partition.

Having more particular reference to the drawing, A designates end, B side, and C 70 top and bottom members or walls, and D a partition, of a box or crate, which in the form shown is of a type commonly used for holding citrus fruits.

As shown, the walls or members A, B and 75 C are formed of separated slats of laminated or other comparatively thin material such as ordinarily employed in articles of this kind, but they also may be formed of slats or the like abutting at their edges or of a single piece in each member.

The top, bottom, and side walls of the container are reinforced with battens 8 secured to their outer sides opposite to the position or positions of the partition or partitions when in place in the container. When only one partition is used in the container, as ordinarily is the case with those for citrus fruits, the reinforcing battens are located substantially midway between 85 the ends of the container, so as to afford compartments of approximately equal capacity.

The partition, in the form disclosed, includes a frame 9, of rectangular shape, arranged to fit snugly in between top, bottom, 90 and sides of the container when they are in normal or unbulged condition, and walls 10 of material that may be the same as or similar to that constituting the outer walls of the container.

100 Adjustable fasteners 11, extending from the edges of the partition, connect the latter to the outer walls of the container and maintain it in place. Each of the fasteners includes an outer terminal apertured head 12, 105 which extends into and slightly outside of a wall of the container and of the batten 8 thereon. Each head is apertured by having an opening or passage 13 extending transversely therethrough. Each fastener has a 110

threaded shank 14 extending through a frame member into the partition and deformed at its inner end as shown at 15. The fasteners also are adapted to be employed with solid partitions in a manner such as disclosed by Fig. 8.

The amount of extension of the fasteners from the edges of the partition may be altered by turning them in threaded members 10 in the partition cooperating with the threaded shanks. The threaded members may be nuts 16, as shown by Figs. 2, 3, and 4, and they may be prevented from turning by their sides abutting against the inner sides 15 of the partition-walls 10 as shown by Figs. 2 and 3 or by being inset into the members of the frame 9, as shown by Fig. 4; or the threaded members may be bushings 17 set into the frame members, as shown by Fig. 5. In either case, the deformed ends 15 of the shanks prevent the fasteners from turning entirely out of the threaded members and their loss when the partition is disassociated from the container, and in the case 25 of nuts they prevent their loss from the shanks. It is understood, of course, that in assembly of parts of the partition the deformation of the shank ends is effected after association of the threaded members with 30 the shanks.

Withdrawal of the fastener-heads from the outer walls of the container and an amount of turning of the fasteners that would result in appreciable alteration of 35 the degree of their extension are prevented by a binding member of a form commonly employed in articles of this kind. This binding member extends around the outside over the battens 8 and through the openings 13 40 in the fastener-heads. When a wire binding member 18, such as shown, is used, the head-openings ordinarily are round, as shown by Fig. 6; and, when a flat metallic strap is employed as the binding member, 45 the head-openings are elongated, as shown by Fig. 7. It is to be understood, of course, that a wire binding member may be employed also with fasteners having elongated head-openings, for they will prevent material turning of the fasteners. Moreover, as 50 the heads usually extend into correspondingly-shaped slots in the container-walls, they also contribute to prevention of turning of the fasteners.

55 When a partition is to be placed in a container, the fasteners 11 of the side and

bottom edges of the partition are turned to bring their heads to the degree of extension desired, dependent upon whether the partition is to hold the bottom and side walls 60 close to its edges or to permit them to bulge therefrom. Ordinarily, if any bulge is to be had at all, it is permitted in the sides and not in the bottom. Then, with the top of 65 the container removed, the partition is inserted between the side walls and against the bottom wall, the side walls bulging sufficiently to permit the fastener-heads to pass to the slots in the walls. Either before or after insertion, the fastener on the 70 top edge of the partition, if any is employed for the top, is adjusted to permit bulge in the top or to hold the top against the partition. Then the top is placed on and the binding manner is passed around the container and through the fastener-heads, and 75 it is drawn tight and fastened in a manner common to the art.

Although only one fastener is shown for purposes of exemplification in each edge of 80 the partition, it is to be understood, of course, that a plurality of them may be employed for association with each side and with the top and bottom of the container, the number being dependent upon the size 85 and character of the container and the uses to which it is put.

It is to be understood also that this invention is susceptible of practical use both with knockdown containers and with those made 90 of parts permanently assembled in the process of manufacture.

Having thus described my invention, what I claim as new, and desire to secure by Letters Patent, is—

1. A partition comprising members constituting a frame having openings therethrough, a wall thereon, bolts in said openings extending inwardly and outwardly of 100 said frame members and having outer terminals disposable into walls of a container, and nuts on the inner portions of said bolts contactable at their sides with said wall whereby their rotation is prevented.

2. A partition comprising a frame, internally threaded members fixed therein, and threaded shanks turnable in said members and extending outwardly beyond the edges of said frame arranged to be associated with 105 walls of a container.

In testimony whereof I affix my signature.
WILLIAM T. S. BROWN.
